Primary Examiner — Keli L Hill*(74) Attorney, Agent, or Firm* — S. Robert Chuey(57) CLAIM

The ornamental design for a cosmetic container, as shown and described.

DESCRIPTION

FIG. 1 is a perspective view of a cosmetic container, embodying our new design;

FIG. 2 is a front view thereof;

FIG. 3 is a top plan view thereof;

FIG. 4 is a bottom view thereof;

FIG. 5 is a side view thereof;

FIG. 6 is a cross sectional view thereof;

FIG. 7 is a perspective view thereof with a cap open;

FIG. 8 is a perspective view of a second embodiment of a cosmetic container, embodying our new design;

FIG. 9 is a front view thereof;

FIG. 10 is a top plan view thereof;

FIG. 11 is a bottom view thereof;

FIG. 12 is a side view thereof;

FIG. 13 is a cross sectional view thereof; and,

FIG. 14 is a perspective view thereof with a cap open.

The broken lines shown are included for the purpose of illustrating the unclaimed portions of the cosmetic container and form no part of the claim.

Back view and one of the side views are omitted because a back view is identical to a front view, and side views are identical to each other.
